UNITED STATES PATENT OFFICE.

WILLIAM M. SCOTT, OF PHILADELPHIA, PENNSYLVANIA, ASSIGNOR TO THE CUTTER ELECTRICAL AND MANUFACTURING COMPANY, A CORPORATION OF NEW JERSEY.

SYSTEM OF REMOTE CONTROL.

1,108,253.

Specification of Letters Patent. Patented Aug. 25, 1914.

Application filed March 8, 1907. Serial No. 361,282.

To all whom it may concern:

Be it known that I, WILLIAM M. SCOTT, a citizen of the United States, residing at Philadelphia, in the county of Philadelphia and State of Pennsylvania, have invented a new and useful System of Remote Control, of which the following is a specification.

My invention relates to a system of control whereby electric switches or automatic circuit breakers included in a circuit may be reset, either manually or by power, the power resetting mechanism being effected by a control circuit or circuits extending to a more or less remote point.

It is the object of my invention to control a setting or resetting of switches or circuit breakers from any desired point more or less distant from the switches or circuit breakers themselves, the control being effected by apparatus controlling an electric motor which supplies the power for setting or resetting the circuit breakers or switches.

My invention resides also in the arrangement of circuits and the apparatus controlled thereby and in the structure of both the control apparatus and the switches or circuit breakers.

My invention resides also in further features hereinafter described and pointed out in the claims.

For an illustration of a form my invention may take reference is to be had to the accompanying drawings, in which:

Figure 1 is a side elevation of an automatic circuit breaker with motor resetting means. Fig. 2 is a front elevation of the apparatus shown in Fig. 1. Fig. 3 is a diagrammatic view showing the circuit arrangements of the system. Fig. 4 is a side view of a commutator segment. Fig. 5 is a side elevation of another commutator segment.

Referring to the drawings, 1 represents a base, of any suitable insulating material, such as slate or marble, upon which is mounted an automatic magnetic circuit breaker A.

Upon the base 1 are mounted the main terminal blocks 2 and 3 which are adapted to be bridged by the laminated bridging member 4 supported by but insulated from the arm 5 pivoted at 6 to the frame or housing 7 secured upon the base 1. Mounted upon and in electrical communication with

the upper terminal block 2 are the stationary shunt metallic contact 8 and the stationary shunt carbon 9, the latter pivoted at 10 to its supporting bracket.

11 and 12 are the movable metallic shunt contact and movable carbon contact engaging respectively with the contacts 8 and 9. 55 The shunt contacts 11 and 12 are insulated from the arm 5 and in electrical communication with each other and by means of the flexible conductor 13 with the lower terminal block 3. Pivoted at 14, in the arm 5, is 60 a roller 15 which is engaged by the cam surface 16 upon the cam member 17 pivoted at 18 to the bracket or housing 7. The cam member 17 has an outwardly extending portion 19 forming an operating handle or 70 lever. A downward projection 20 has pivoted therein at 21 the roller 22, adapted to be engaged by the latch 23 pivoted at 24 to the bracket 7. Pivoted concentrically with the latch 23, on the axis 24, is a latch actuating member 25 carrying at its forward end an adjustable screw 26 adapted to engage upon the top of the latch 23. An overload tripping device comprises an armature 27 which, when attracted, raises the lever 80 28 to actuate the latch 23. There is, also, a tripping mechanism responsive to reversed flow comprising the magnet windings 29 and 30 pivoted armature member 31 which connects by rod 32 to the latch 23 to actuate 85 the same. Secured to the latch actuating member 25 is a rearwardly and outwardly extending member 33 having the heel 33'. An additional opening coil 37 is provided for tripping the breaker which is effected by 90 energizing said coil 37 whereupon the core 36, having the head 38, adjustable by screw 39 in the stirrup 40, rises and strikes the pin 35 which in turn strikes the heel 33' of the member 33 thus actuating the latch 95 member 25 to trip the circuit breaker.

The circuit breaker may be manually closed or reset by depressing the operating lever 19 which is in elevated position when the circuit breaker is opened. By depressing the lever 19 the cam surface 16 engages with the roller 15 on the arm 5 pushing the lever 5 toward the base. At first, the movement of the arm 5 is quite rapid due to the shape of the cam surface, but after the laminated bridging member 4 engages the main

terminal blocks 2 and 3 the movement is much slighter though the operating lever 19 moves through relatively great space, thus serving to cramp the member 4 into contact with the main terminals 2 and 3. When the parts reach full circuit closing position the latch 23 catches the roller 22 carried by the cam member 17, thus locking the parts in circuit closing position.

Upon the occurrence of an abnormal circuit condition, such as an overload or reversed energy flow, the latch 23 is actuated thus releasing the cam member 17 and allowing the parts to spring to open circuit position. In opening circuit the laminated bridging member 4 first separates from the main terminals 2 and 3, later the metallic shunt contact 11 separates from the stationary metallic shunt contact 8, and finally, the shunt carbon 12 separates from the shunt carbon 9 and the final arcing takes place between these carbons in the well known manner.

To reset the circuit breaker by power, an electric motor M is provided and is here shown as a series wound motor; that is, the field winding and the armature are in series with each other. The motor shaft 41 has secured upon its outer end a member 42 comprising in one part the worm 43 and in another the rotatable element 44 of a brake. The worm 43 engages with the worm wheel 45 secured upon a shaft 46 revolving in the bearings 47, 48. On one end of the shaft 46 is carried a crank 49. The outer end of the crank 49 is adapted to engage the end of crank 51 secured upon the shaft 52 supported in bearing 53, having secured upon its other end the crank 54 carrying at its outer end a pin upon which is rotatably secured the rod 55. The rod 55 is connected to the crank 54 for positive driving in either direction, while the crank 49 is not connected to the crank 51, except by spring 50, and is adapted to drive crank 51 only in one direction.

Supported upon the motor M by brackets 61 and 62 is the housing 63 of an electromagnet whose winding 64 is located within the same and surrounds the core 65. 66 is the armature mounted upon the rod 67 which extends through the core and out through the housing and engages the lever 68 pivoted to the frame at 69. Two springs 70 are secured to a cross bar 71 at the top of the lever 68 and their other ends are secured to ears 72 on the housing 63. Coöoperating with the rotatable brake element 44, which is in the form of a hollow truncated cone, is the brake shoe 73 of complementary form pivoted at 74 to the lever 68. In the operating lever 19 of the circuit breaker is a transversely extending pin 19'. The pin 19' engages in the slot 75, in the member 76 secured upon the upper end of the rod 55, and adjustable thereon by the screw threads 77 and nuts 78.

This connection of the member 76 to the rod 55 amounts in effect to a means for adjusting the effective length of the rod 55 between the upper end of the slot 75 and the crank pin in the crank 54.

Supported upon the same base with the worm wheel and cranks is the vertically disposed plate of insulating material 83 secured to the vertical standard or bracket 84. Supported by the plate 83, which may be of slate, is the shaft 85 coaxial with the shaft of the worm wheel and cranks. Rotatable upon the shaft 85 are two contact rings or segments 86 and 87, shown in larger scale in Figs. 4 and 5, separated from each other by the member 88 of insulating material, and both in electrical communication with the shaft 85. A circular disk 89, of insulating material, forms the outer member of this rotatable commutator, all the elements of which are mechanically secured together to rotate upon the shaft 85. The commutator is rotated by a crank 54 through the agency of the crank-like member 90, secured to the insulating disk 89. The contact rings 86 and 87 are not circumferentially continuous. The conducting disk 86 is continuous only through a little more than half a circumference, while the disk or segment 87 extends through a little less than half a circumference. A brush holder 91 is secured to the plate 83 and supports the two brushes 92 and 93, bearing upon 86 and 87 respectively.

Referring to Fig. 3, 94 and 95 represent respectively the positive and negative bus bars with which the generator G is adapted to communicate through the circuit breaker A and the conductor 96. M' is the armature of the series motor M, the series field being represented at S'. The series field and the winding 64 of the brake magnet are connected in parallel with each other and in series with the armature.

A switch lever 97, located at any point more or less remote from the circuit breaker A, is pivoted at 98 and connects by the conductor 99 with the two commutator segments 86 and 87, as through the commutator shaft 85. The switch lever 97 has a normal tendency to remain in central position as shown in Fig. 3, due to the opposing springs 100 and 101, and in this position engages the middle of the three contacts 102, 103, and 104. The contact 102 is in communication with a positive conductor 102' of the system through the winding 105 of the low voltage or underload magnet whose core 106 is adapted to hold the lever 97 in engagement with contact 102 when the armature 107 is held attracted by the core 106. Similarly, the contact 104 connects through the winding 108 of a low voltage or underload magnet, whose core is 109, with a negative conductor 104' of the system. And similarly, the switch lever 97 is adapted to be held in

contact with contact 104 when the armature 110 is held attracted by the core 109. L is an ordinary incandescent lamp having its terminals connected to the contacts 102 and 103 respectively and serves merely as a visual indicator that the circuits at the operating mechanism for the breaker A are in readiness to operate as soon as the lever 97 is placed on contact 102.

10 The armature 66 of the brake magnet is adapted to carry the contact 111 which, when the armature 66 is in the attracted position, bridges the contacts 112 and 113.

15 The operation is as follows:—With the parts in the position as shown in Fig. 1, the motor has just completed the closing movement of the circuit breaker and the breaker is locked in circuit closing position. The crank 54 has been moved by the motor just

20 past the dead-center position. Should the circuit breaker now be tripped by any of the means provided, as the overload tripping mechanism, reversed energy flow tripping mechanism, opening coil 37, or by hand, the operator's handle 19 will be rotated in a counter-clockwise direction, as seen in Fig. 1, about its pivot 18, and will raise the rod 55 until, when the operator's lever 19 is in uppermost position, the crank 54 will be just

25 past the dead-center position after having rotated in the direction of the arrow to an almost vertical position. The spring 50, connected at one end to the hub of the crank 54 and at its other end to the outer end of the crank 49, prevents overtravel of the crank 54, so that it never reaches dead-center position or beyond, and accordingly any manual operation of the lever 19 will not disarrange the desired relation of cranks 49

30 and 54. The parts having rotated to this upper position, the commutator has been rotated so that the brush 92 has just come on to the segment 86. The lamp L is then lighted or glowing and an operator at the

35 switch 97 knows that the circuit breaker is

open and that the parts are in position ready to operate to close the breaker. The operator accordingly moves the switch lever 97 over on to contact 102 and accordingly cur-

40 rent will flow from positive conductor 102' through the underload coil 105, contact 106,

switch 97, conductor 99 to the common connec-

45 tion for segments 86 and 87, through 86,

brush 92, series field S', and the brake coil 64

50 in parallel with it, motor armature M', and

conductor 96 to the negative bus 95. In

consequence, the brake coil winding 64 is

55 energized and the armature 66 is attracted

thereby pushing upon rod 67 to force the

60 lever 68 to the right, as seen in Fig. 1,

against the opposition of the springs 70, thus

lifting the brake shoe 73 from the brake

65 member 44. The motor accordingly starts

and drives the wheel 45 by the worm 43

65 which causes the crank 49 to move around

to the previously elevated crank 54, to engage the same and to drive the same around in a clockwise direction, as viewed in Fig. 1, to resume the position of parts shown in Fig. 1. Just before this position is reached, 70 the brush 92 snaps off of the point 86' of the segment 86 on to insulating material and the motor circuit is accordingly broken, and the brake coil 64 de-energized, allowing the springs 70 to set the brake and bring the 75 parts to a stop.

When the brake magnet is energized, the contact 111 bridges contacts 112, and 113, thus closing circuit through the motor independent of the distant switch 97, so that 80 when the switch 97 has instituted the movement, the movement will continue until the parts assume the position as shown in Fig. 1.

The closing of the circuit through contacts 112 and 113 greatly diminishes the current through the switch 97 so that the underload magnet 105 releases the switch lever and it assumes middle position under the control of the springs 100 and 101. If, 90 for any other reason the current in the circuit should be greatly reduced the underload magnet will release switch 97 to allow it to assume this middle position.

When the motor circuit has been interrupted by the brush 92 leaving segment 86, brush 93 has come into communication with segment 87, so that, if it is desired to trip breaker A from a distance, the switch 97 is moved into engagement with contact 104, 100 whereby there is a circuit from the positive bus 94 through the breaker A, opening coil, 37, brush 93, segment 87, conductor 99, switch 97, the contact 104, and negative conductor 104'. This causes the rise of 105 the core 36 of the opening coil causing the tripping of the breaker in a well known manner. And, as aforesaid, the tripping of the breaker moves the rod 55 and crank 54 and the commutator to such position that 110 again moving the switch 97 to the contact 102 will start the motor to close the breaker.

What I claim is:—

1. In combination, a circuit breaker, tripping means therefor, a motor for resetting 115 said breaker, a rod having pin and slot connection with the operating member of said circuit breaker, a crank for operating said rod, a second crank having lost motion with respect to said first mentioned crank, 120 and a motor for driving said second crank.

2. In combination, a circuit breaker, a series motor for actuating the same, a brake for said motor, and an electro-magnet for lifting said brake when said motor is started, the winding of said electro-magnet being connected in shunt with the field winding of said motor. 125

3. In combination, a circuit breaker, a series motor for operating the same, a brake 130

for said motor, and an electro-magnet for lifting said brake when the motor is started, the winding of said electro-magnet being connected in shunt with the field winding of said motor, said electro-magnet being deenergized for setting the brake when said motor is deenergized.

4. In combination, a circuit breaker, a motor for operating the same, a coil for tripping said circuit breaker independently of said motor, a crank and rod connection to the operating member of said circuit breaker, a second crank driven by said motor to drive said crank and rod connection, a switch for controlling said motor, the movable member of said switch movable in fixed relation with respect to said first mentioned crank, and a switch having contacts in the circuits of said tripping coil and said motor control switch.

5. In combination, a circuit breaker, automatic means for tripping the same, a motor for resetting the breaker, a crank and rod connection with the operating member of said breaker, a lost motion connection between said crank and operating member of the breaker, and a lost motion connection between said motor and said crank.

6. In combination, a circuit breaker, a tripping coil therefor, a rod having a lost motion connection with the operating member of said breaker, a crank connected to said rod, a motor, a second crank driven by said motor, said second crank adapted to drive said first mentioned crank and having lost motion with respect thereto, a switch controlling said motor, the movable member of said switch movable in fixed relation with said first mentioned crank, and an operator's switch controlling the circuits of said switch and said tripping coil.

7. In combination, a circuit breaker, a tripping coil therefor, a crank having lost motion connection with the movable member of said circuit breaker, a second crank adapted to drive said first mentioned crank and having lost motion with respect thereto, a motor for driving said second crank, said motor actuating said circuit breaker in one direction only after it has been tripped by said tripping coil, and a switch controlling said motor, the movable member of said switch actuated in fixed relation with said first mentioned crank for opening said switch to break the circuit of said motor when said circuit breaker is reset, said switch being closed when said circuit breaker opens.

8. In combination, a circuit breaker, a coil for tripping the same, a member having lost motion with the operating member of said circuit breaker, a second member adapted to operate said first mentioned member and having lost motion with respect thereto, a motor for actuating said second member,

and switches controlling the circuits of said motor and said tripping coil, the movable members of said switches being operated in fixed relation with respect to said first mentioned member for opening the circuit of said motor when said circuit breaker is reset and for closing the circuit of said tripping coil when said circuit breaker is reset.

9. In combination, a circuit breaker, a motor for resetting the same, a motor brake, a magnet for lifting the brake when the motor is energized, the winding of said magnet being connected in parallel with a winding of said motor, a switch controlling the circuit of said motor and brake magnet, and means for shifting said switch by the tripping of said breaker.

10. In combination, a circuit breaker, a motor for operating the same, a brake for said motor, an electro-magnet for operating said brake, the winding of said electro-magnet being connected in shunt with a winding of said motor, a switch controlling said motor movable with the movable member of said breaker to break the circuit of said magnet when said breaker is reset, an operator's switch, and a switch controlled by said electro-magnet winding for holding the motor circuit closed independently of said operator's switch.

11. In combination, a circuit breaker, a motor for operating the same, a rod having a lost motion connection with the operating member of said breaker, a crank connected to said rod, a second crank driven by said motor, said cranks having lost motion with respect to each other, and a spring connecting said cranks.

12. The combination with a circuit breaker, of a motor moving always in the same direction for resetting the same, a tripping coil for said circuit breaker, switches controlling the circuits of said motor and said tripping coil, and an operator's switch, said operator's switch being alternately in series with said motor and said tripping coil, the movable members of said motor and tripping coil switches being mechanically connected.

13. In combination, a circuit breaker, a motor for resetting the same, a brake for said motor, a winding for operating said brake, means for starting said motor from a distance, and means actuated by said brake winding for maintaining the motor circuit closed after being closed at a distance.

14. In combination, a circuit breaker, a latch therefor, a tripping coil for said latch, a motor for operating said breaker in one direction only to latching position, a worm wheel driven by said motor, a crank connected with said worm wheel, a second crank driven always in the same direction by said first mentioned crank and having

lost motion with respect thereto, a rod connected to said second crank and having lost motion connection with the movable member of said circuit breaker, and a motor 5 controlling switch having its movable member movable in fixed relation with said second crank.

15. In combination, a circuit breaker, a motor for operating the same, a crank 10 driven by said motor, a second crank driven by said first mentioned crank and having lost motion with respect thereto, a rod driven by said second crank and having lost motion connection with the movable 15 member of said circuit breaker, said second crank and rod being just over dead-center when said motor has reset said breaker.

16. The combination with the movable member of a circuit breaker, of a motor, 20 means for driving said movable member in one direction only intervening between said motor and said movable member and having lost motion with respect to said motor and with respect to said movable member, a tripping coil for said circuit breaker, a switch 25 for controlling said motor, the movable member of said switch movable in fixed relation with said driving means, and a switch having contacts in the circuits of said tripping 30 coil and said motor control switch.

17. In combination, a circuit breaker, a motor for operating the same, a crank driven always in the same direction by said motor, a second crank driven by said first mentioned crank and having lost motion with respect thereto, a lost motion connection between said second crank and the operating member of said circuit breaker, and a motor controlling switch movable with said second 40 crank.

18. The combination with an electric switch, of a motor for closing the same, a brake for said motor, an electro-magnet controlling said brake, an operator's switch for 45 simultaneously closing the circuit of said motor and said electro-magnet, a switch closed by said electro-magnet for maintaining the motor circuit closed after the motor has been started through said operator's 50 switch, and means for automatically opening the circuit of said motor at the end of the switch closing movement.

19. The combination with an electric switch, of a motor for operating the same, 55 a latch for said switch, a tripping coil for said latch, a motor driven crank, a second crank driven by and having lost motion with respect to said first crank, a rod connected with said second crank, and a pin and slot 60 connection between said rod and the movable member of said switch, said switch when tripped opening independently of said motor, and said motor moving said switch in one direction only to latching position.

65 20. The combination with an electric

switch, of a coil for tripping the same, a motor for actuating said switch, a crank driven by said motor, a second crank driven by and having lost motion with respect to said first crank, a frame supporting the 70 shafts of said cranks in substantial axial alinement, and switches controlling the circuits of said motor and said tripping coil, the rotating members of said switches being mounted coaxially with said crank shafts. 75

21. In combination, a movable contact member, a rod and crank connection with said contact member, a motor, a second crank driven thereby, a lost motion connection between said cranks, means engaging 80 said cranks preventing said rod and crank connection assuming a dead-center position, and a motor controlling contact movable in definite relation with said rod and crank connection. 85

22. In combination, a movable contact member, a rod and crank connection with said contact member, a motor, a second crank driven thereby, a lost motion connection between said cranks, means engaging said 90 cranks preventing said rod and crank connection assuming a dead-center position, a motor controlling contact movable in definite relation with said rod and crank connection, and a remote switch controlling 95 said motor.

23. In combination, a movable contact member, a rod and crank connection with said contact member, a motor, a second crank driven thereby, a lost motion connection between said cranks, and means on said 100 second crank for preventing said rod and crank connection assuming a dead-center position.

24. In combination, an electric switch, an 105 operating member therefor, a crank having a lost motion connection with said operating member, a motor, a second crank driven by said motor, a lost motion connection between said cranks, and means engaging said cranks 110 for preventing said first mentioned crank assuming a dead-center position.

25. The combination with an electric switch, of a latch for restraining the same in normal position, a motor rotating always 115 in one direction for closing said switch, means for tripping said switch, the opening of said switch being independent of either actuation or control by said motor, and a switch having contacts controlling said 120 motor and said tripping means respectively.

26. The combination with an electric switch, of a motor rotating always in one direction for closing the same, a crank and rod connection between said motor and said 125 switch, the opening of said switch being independent of either actuation or control by said motor, a tripping coil for said electric switch, a switch controlling said tripping coil, a switch controlling said motor, 130

said tripping coil and motor switches having their movable members movable in fixed relation with said rod and crank connection.

27. The combination with an electric switch, of a motor for closing the same, a coil for tripping said electric switch independently of said motor, means for closing the circuit of said motor to start the same, automatic means for maintaining the motor circuit closed until said switch has been closed by said motor, and a switch for breaking the motor circuit when said switch is closed.

28. The combination with an electric switch, of a coil for tripping the same, a motor rotating always in one direction for restoring said switch only, a motor control switch breaking the circuit of said motor when said electric switch has been restored, and a lost motion connection between said electric switch and said motor control switch for resetting said motor control switch in response to the opening movement of said electric switch.

29. The combination with an electric switch, of a motor rotating always in the same direction for closing the same, an operator's switch for closing the circuit of the motor to start the same, automatic means for maintaining the motor circuit closed independently of said operator's switch, and a switch for breaking the motor circuit when said switch reaches closed position.

30. The combination with an electric switch, of a motor rotating always in the same direction for closing the same, an operator's switch for closing the circuit of said motor to start the same, and a motor circuit switch for rupturing the circuit of said motor at the end of the switch closing movement, said motor circuit switch being closed independently of said motor by the opening movement of said switch, a coil for tripping said electric switch controlled by said operator's switch.

31. The combination with an electric switch, of a latch, a tripping coil therefor, a motor for closing said switch, the opening of said switch being independent of either actuation or control of said motor, a distant switch manually operated independently of said electric switch for closing the circuit of said tripping coil or of said motor to start the same, and an automatic switch in said motor circuit for rupturing said motor circuit at the end of the switch closing movement and for automatically restoring said motor circuit upon the opening of said switch, said motor circuit switch being closed by the opening movement of said switch.

32. The combination with an electric switch, of a motor for closing the same, an operator's switch for closing the circuit of said motor for starting the same, automatic

means for maintaining said motor circuit closed independently of said operator's switch, and an automatic switch in said motor circuit for rupturing said motor circuit at the end of the switch closing movement and for automatically restoring said motor circuit after said switch has opened, said motor circuit switch being closed by the opening movement of said switch.

33. The combination with an electric switch, of a motor for actuating the same, a crank and rod connection between said motor and said switch, an automatic switch in the circuit of said motor and actuated by said motor to rupture the circuit of said motor, and actuated by the opening movement of said switch by said crank and rod connection independently of said motor to restore said motor circuit, a coil for tripping said electric switch, and an operator's switch having different contacts controlling said motor and said tripping coil.

34. The combination with a main switch, of means for locking the same in normal position, means for tripping said switch, of a motor rotating always in the same direction for moving said main switch to normal position, a motor control switch automatically rupturing the circuit of said motor after predetermined movement of said main switch by said motor and actuated by said main switch independently of said motor when said main switch is tripped, a second switch controlling said motor through said motor control switch, and a switch automatically maintaining the circuit of said motor closed after it has once been closed by said second switch.

35. The combination with a main switch, of a motor for actuating the same, a brake for said motor, an electro-magnet for lifting said brake, a switch controlling the circuit of said magnet and said motor for lifting said brake and starting said motor, and a switch controlled by said electro-magnet for maintaining the circuit of said motor closed after it has once been closed by said switch.

36. The combination with a main switch, of a latch for restraining the same in normal position, a tripping coil, a motor rotating always in one direction for closing said main switch, the opening of said main switch being independent of either actuation or control by said motor, a double throw operator's switch, and connections whereby said operator's switch in one position energizes said tripping coil to trip said main switch and in its other position closes circuit through said motor independently of said trip coil to energize said motor to return said main switch to normal position.

37. The combination with a main switch, of a latch for restraining the same in normal position, a tripping coil, a motor rotating always in one direction for closing said

- main switch, the opening of said main switch being independent of either actuation or control by said motor, a double throw operator's switch, connections whereby said operator's switch in one position energizes said tripping coil to trip said main switch and in its other position closes circuit through said motor independently of said trip coil to energize said motor to return 5 said main switch to normal position, and a switch for breaking the circuit of said motor when said main switch has reached normal position. 38. The combination with a main switch, 10 of means for restraining the same in normal position, a trip coil therefor, a motor for moving said main switch to normal position, a double throw operator's switch which in one position energizes said trip coil to trip 15 said main switch and in its other position energizes said motor for returning said main switch to normal position, and a second switch actuated by said motor for breaking the circuit of said motor when said main 20 switch reaches normal position and actuated independently of said motor by said main switch when tripped to reestablish said 25 motor circuit. 39. The combination with a main switch, 30 of means for restraining the same in normal position, a trip coil therefor, a motor for moving said main switch to normal position, a double throw operator's switch which in one position energizes said trip coil to 35 trip said main switch and in its other position energizes said motor for returning said main switch to normal position, a second switch actuated by said motor for breaking the circuit of said motor when said main 40 switch reaches normal position and actuated independently of said motor by said main switch when tripped to reestablish said motor circuit, and a third switch movable with said second switch controlling said trip 45 coil. 40. The combination with a main switch, 50 of means for restraining the same in normal position, a trip coil therefor, a motor for moving said main switch to normal position, a double throw operator's switch which in one position energizes said trip coil to trip said main switch and in its other position energizes said motor for returning said main switch to normal position, a second switch actuated by said motor for breaking the circuit of said motor when said main 55 switch reaches normal position and actuated independently of said motor by said main switch when tripped to reestablish said motor circuit, and an automatic switch 60 maintaining the circuit of said motor closed after it has once been closed by said operator's switch. 41. The combination with an electric 65 switch, of a motor for closing the same, an operator's switch for closing the circuit of said motor for starting the same, automatic means for maintaining said motor circuit closed independently of said operator's switch, and an automatic switch in said motor circuit for rupturing said motor circuit at the end of the switch closing movement and for automatically restoring said motor circuit after said switch has opened, 70 said motor circuit switch being closed by the opening movement of said switch. 42. The combination with a main switch, 75 of a motor for actuating the same, an operator's switch for closing the circuit of said motor for starting the same, an electro-magnet for holding said operator's switch in starting position, and automatic means operative after said motor circuit has been closed by said operator's switch for maintaining said motor circuit closed independently of said operator's switch and for causing said electro-magnet to release said operator's switch. 43. The combination with an electric 80 switch, of a circuit controlled thereby, of a motor for actuating said switch, means independent of the electrical conditions in said circuit for closing the circuit of said motor for starting the same, means for holding said means in motor starting position, and automatic means for maintaining said motor circuit closed independently of said first named means and for releasing the same from said holding means. 44. The combination with a main switch, 85 of a trip coil therefor, a motor for actuating said main switch, an operator's switch in one position closing the circuit of said motor for starting the same and in another position closing the circuit of said trip coil, and an electro-magnetic switch operative after said motor circuit has been closed by said operator's switch for maintaining said motor circuit closed independently of said operator's switch. 90 45. The combination with a main switch, 95 of a trip coil therefor, a motor for actuating said main switch, an operator's switch in one position closing the circuit of said motor for starting the same and in another position closing the circuit of said trip coil, and an electro-magnetic switch operative after said motor circuit has been closed by said operator's switch for maintaining said motor circuit closed independently of said operator's switch, said operator's switch controlling 100 said electro-magnetic switch. 46. The combination with an electric 105 switch, of a motor for actuating the same, a switch for starting said motor, means for holding the same in starting position, an electro-magnet controlled by said switch, and a switch controlled by said electro-magnet for maintaining said motor circuit closed independently of said motor starting switch. 110 115 120 125 130

and for releasing the same from said holding means.

47. The combination with an electric switch, of means restraining the same in normal position, tripping means therefor, a motor for moving said switch to normal position, a switch for starting said motor, an electro-magnet controlled by said switch, and a switch controlled by said electro-magnet and controlling the circuit of said electro-magnet for maintaining said motor circuit closed independently of said motor starting switch.

48. The combination with a main switch, of means for tripping the same, a motor rotating always in the same direction for returning said main switch to normal position after having been tripped, an operator's switch for starting said motor, automatic means for maintaining said motor circuit closed independently of said operator's switch, and a motor control switch for holding said motor circuit open after predetermined movement of said main switch and for closing said motor circuit after said main switch has been tripped.

49. The combination with a main switch, of a motor for actuating the same, an operator's switch for closing the circuit of said motor, an electro-magnet whose winding is brought into circuit by said operator's switch for holding said operator's switch in circuit closing position, and automatic means operative after said motor circuit has been closed by said operator's switch for maintaining said motor circuit closed independently of said operator's switch and for causing said electro-magnet to release said operator's switch.

50. The combination with a main switch, of a motor for actuating the same, an operator's switch for closing the circuit of said motor, an electro-magnet for holding said operator's switch in circuit closing position, a second electro-magnet controlled by said operator's switch, and a switch controlled by said second electro-magnet for maintaining said motor circuit closed independently of said operator's switch.

51. The combination with a main switch, of a motor for actuating the same, an operator's switch for closing the circuit of said motor, an electro-magnet for holding said operator's switch in circuit closing position, a second electro-magnet controlled by said operator's switch, and a switch controlled by said second electro-magnet for maintaining said motor circuit closed independently of said operator's switch and for causing said first named electro-magnet to release said operator's switch.

52. The combination with a main switch, of means for tripping the same, a motor for returning said main switch to normal position after having been tripped, a switch

for starting said motor, an automatic switch for maintaining said motor circuit closed independently of said starting switch, and a motor control switch actuated in one direction by said motor for breaking the motor circuit after predetermined movement of said main switch and actuated in opposite direction by the opening movement of said main switch independently of said motor for reestablishing said motor circuit.

53. The combination with a main switch, of a trip coil therefor, a motor for actuating said main switch, a double throw automatic switch in one position controlling said trip coil and in another position controlling said motor, an operator's switch controlling said motor through said double throw automatic switch in one of its positions, and means for maintaining the circuit of said motor closed after having once been closed by said operator's switch.

54. The combination with a main switch, of a trip coil therefor, a motor for actuating said main switch, a double throw automatic switch in one position controlling said trip coil and in another position controlling said motor, and a double throw control switch in series with said automatic double throw switch.

55. The combination with a main switch, of a trip coil therefor, a motor for actuating said main switch, a double throw automatic switch in one position controlling said trip coil and in another position controlling said motor, a double throw control switch, and a single conductor extending between said double throw switches and connecting them in series with each other.

56. The combination with a main switch, of a trip coil therefor, a motor for actuating said main switch, a double throw automatic switch in one position controlling said trip coil and in another position controlling said motor, a double throw control switch in series with said automatic double throw switch, and an automatic switch controlled by said double throw control switch for maintaining the circuit of said motor closed independently of said double throw control switch.

57. The combination with a main switch, of a trip coil therefor, a motor for actuating said main switch, a double throw automatic switch in one position controlling said trip coil and in another position controlling said motor, a double throw control switch, a single conductor extending between said double throw switches and connecting them in series with each other, and an automatic switch controlled by said double throw control switch for maintaining the circuit of said motor closed independently of said double throw control switch.

58. The combination with a main switch, of a trip coil therefor, a motor for actuating said main switch, a double throw automatic

switch in one position controlling said trip coil and in another position controlling said motor, a double throw control switch in series with said automatic double throw switch, and means for causing said automatic double throw switch to take different positions in accordance with different positions of said main switch.

In witness whereof, I hereunto set my hand in the presence of the two subscribing ¹⁰ witnesses.

WILLIAM M. SCOTT.
